CLAIM

The ornamental design for a golf aid as shown and described.

DESCRIPTION

FIG. 1 is a top perspective view of the golf aid;

FIG. 2 is a bottom perspective view thereof;

FIG. 3 is a bottom view thereof;

FIG. 4 is top view thereof;

FIG. 5 is a side view thereof; and,

FIG. 6 is a side view thereof.

The claim is directed to the collective appearance of the golf aid shown in the figures. The relative positioning of the parts does not form part of the claimed design. The dashed lines are for the purpose of illustrating elements of the golf aid and form no part of the claimed design.
